G. MANASSERO

ANTIFREEZING WATER HEATER FOR INTERNAL COMBUSTION MOTORS

Filed Jan. 2, 1926

INVENTOR.

BY

Giuseppe Manassero
Soltan P. Polackoff
ATTORNEY

UNITED STATES PATENT OFFICE.

GIUSEPPE MANASSERO, OF BRONX, NEW YORK.

ANTIFREEZING WATER HEATER FOR INTERNAL-COMBUSTION MOTORS.

Application filed January 2, 1926. Serial No. 78,759.

This invention relates to a new and useful device in the nature of an antifreezing water heater, the device being particularly adapted for use in connection with water cooled internal combustion engines for the purpose of heating the cooling water to prevent freezing in cold weather.

The object of the invention is to provide an antifreezing water heater of novel construction and arrangement of parts, herein-after more fully described, claimed, and illustrated in the accompanying drawing, in which:—

Fig. 1 shows a side elevational view of an internal combustion engine and cooling radiator, such as used in motor vehicles, with my improved device attached thereto.

Fig. 2 is a vertical central sectional view of my improved device.

Fig. 3 is a sectional view taken on the line 3—3 of Figure 2.

Fig. 4 is a sectional view taken on the line 4—4 of Figure 2, and also shows a diagrammatic view of the wiring for my improved device.

Fig. 5 is an enlarged fragmentary sectional view taken on the line 5—5 of Figure 3.

Fig. 6 is a sectional view taken on the line 6—6 of Figure 2. Fig. 7 is an enlarged sectional view of the temperature regulating pin.

Fig. 8 is a schematic wiring diagram of the device.

The internal combustion engine 10, is provided with a fan 11, driven by a suitable belt 11, a water pump 12, attached to the water jacket 13, and connected to the cooling radiator 14 by means of a hose 15. The water outlet manifold 16 is also connected to the cooling radiator 14 by means of a second hose 17. The above mentioned parts are common construction and such as ordinarily used in motor vehicles, aeroplanes, and the like.

It will be understood that my improved device, designated by the numeral 18 is suitably connected to the hose 15, or to the hose 17, as clearly shown in Figure 1 of the accompanying drawing.

As here embodied my improved devi-
comprises a body 19, of hollow cylindrical construction, and having two outlets 20 and 21, oppositely located. The body 19 is also provided with an aperture to receive the supporting member 22, which is removably

attached to the upper extremity of the body 19, by threads, or any similar means. The supporting member 22 is of hollow construction, and has a lower protruding portion 23, located between the heretobefore mentioned two outlets 20 and 21 of the body 19.

The plug 24, is removably attached to the lower protruding portion 23 of the supporting member 22, by threads, or any similar means. The plug 24 has an axial cylindrical recess 25. The heating element has a lower portion 26, a slidable fit on the periphery of the upper portion of the plug 24, and is coated with asbestos, 27, or any similar non-heat conducting material, the shell 28 is provided to protect the asbestos 27, the shell 28 is a slidable fit in the lower portion of the body 19. The flange 29 of the heating element is also insulated from the body 19 by asbestos 30, or any similar non-heat conducting material.

The lower insulating block 31, preferably of hard rubber, is of hollow cylindrical construction, a slidable fit in the supporting member 22. The upper insulating block 32, of similar material is also of hollow cylindrical construction, a slidable fit in the supporting member 22, and has an upper protruding portion 33.

The heating element, by its flange 29, the lower insulating block 31, and the upper insulating block 32, are attached to each other by means of screws 34.

The disc 35, circular shaped is located in the lower insulating block 31, and has prongs 36 protruding downwardly in the lower insulating block 31.

The pin 38 is a slidable fit in the upper insulating block 32 and has preferably, portions 38', of somewhat larger diameter in the pin proper. The pin 38 has suitably attached thereto, by a flange 39, a second disc 54, having a protruding central portion 54'. It being understood that the said protruding central portion is normally in contact with the disc 35, and that the said second disc encloses or seals the axial aperture 55 and the semicircular recess 56 in the pin 38, and that the said axial aperture and the said semicircular recess are filled with mercury, or any similar substance before the second disc 54 is attached to the pin 38.

The circuit breaker 40 is adjustably attached to the upper extremity of the pin 38 by means of nuts 41, screwed thereon. The circuit breaker 40 has down-

wardly protruding portions 42, a slidable fit in apertures suitably located in the protruding portion 33 of the upper insulating block 32.

5 The coil spring 43 is superimposed between the upper insulating block 32 and the disc 39, and is located in a circular slot 44, so as to normally hold the disc 39 in a downward position, in contact with the dia-
10 phragm 35.

The contact points 49 and 50 are connected to the screws 34 by the extended portions 51.

The cap 45 or cover is removably attached 15 to the supporting member 22 by threads, or any similar suitable means, and is provided with a plurality of apertures 57 conveniently located in its sides above the supporting member 22, and has also a centrally located 20 aperture at its top, to accommodate a bushing 48, preferably of hard rubber, suitably attached thereto through which the insulated electric wires 58, 59, 60 and 61 are passed.

25 The wire 58 is connected to the one of the screws 34 and to the electric light 53, the wire 59 is connected to the same screw 34 and to a socket 62, of ordinary construction, such as would be used to connect my im-
30 proved device to an electric circuit, the wire 59 has connected thereto a wire 63 which is also connected to a storage battery 52. The wire 61 is connected to the socket 32, and a wire 66 is connected to the wire 61
35 and to the storage battery 52. Switches, of ordinary construction, 64 and 65, are provided in the two circuits.

It will be further understood that functioning or operation of my improved device 40 is as follows: By means of the electric current through the lower portion 26 of the heating element, the water used to cool the engine will be heated, when the water has been heated to the desired temperature, the
45 heat from the heating element will expand the second disc 54 which will raise the pin 38, the circuit breaker 40 will be raised also and the electric current will no longer flow through the heating element.

50 It will be further understood that the superimposed coil spring 43 will cause the circuit breaker 40 to return or drop to a normal position when the second disc 35 becomes cool and returns to its normal position, which will again allow the electric current to flow through the heating element, and the operation will again be repeated, when the cooling water of the engine has been heated to the desired temperature.

55 It will also be understood that the electric light bulb will be lighted only when the electric current is flowing through the heating element.

60 It will also be understood that the nuts 65 41 screwed onto the upper extremity

of the pin 38, may be adjusted to regulate the functioning of my improved device, by raising or lowering the circuit breaker 40.

While I have above described the preferred form, construction and arrangement of the several elements employed, it will be understood that the device is nevertheless, susceptible of considerable modification therein, and I therefore reserve the privilege 70 of resorting to all such changes as may be fairly embodied within the spirit and scope of the invention as claimed.

Having thus described my invention, what I claim as new, and desire to protect by Letters Patent of the United States is as follows:—

1. In a device of the class described, having a heating element, the combination of a hollow cylindrical body having two outlets, 80 oppositely located, said body being provided with an aperture to receive a supporting member, removably attached thereto, said supporting member being of hollow construction and having a lower protruding portion located between the said two outlets, a plug removably attached to the said lower protruding portion, said plug having a cylindrical recess, supporting said heating element, said heating element being insulated, 85 and provided with a shell to support the said insulation, a lower insulating block, and an upper insulating block of hollow cylindrical construction, both blocks being a slid-
90 able fit in the said supporting member, a disc located in the lower insulating block, said disc being attached to a pin having an axial aperture and a semicircular recess, said disc being located so as to be in contact with another disc, said pin being a slid-
95 able fit in the said upper insulating block, a contact adjustably attached to the upper extremity of the said pin, said contact normally in contact with other contact points, and a coil spring superimposed between the said upper insulating block and the said pin, to normally hold the said pin in a downward position.

2. In a device of the class described, having a heating element, the combination of 115 a body provided with a threaded aperture, a supporting member engaged in said aperture, a lower protruding portion depending from said supporting member, a plug removably attached to the said protruding portion and supporting said heating element, a lower insulating block, and an upper insulating block suitably supported in said supporting member, a disc located in the lower insulating block, a pin having an axial aperture and a semicircular recess, attached to said disc, a second disc located in the said lower insulating block, and contactable with said disc, a contact adjustably attached to the upper extremity of said pin, 120 125 130

another contact normally in contact, and a coil spring superimposed between the said upper insulating block and the said pin, normally holding said pin in a downward 5 position.

3. In a device of the class described, having a heating element, the combination of a body, a supporting member engaged in said body, a lower protruding portion depending from said supporting member, a plug removably attached to the said protruding portion, and supporting said heating element, a lower insulating block, and an upper insulating block suitably supported 10 in said supporting member, a disc located in the lower insulating block, a pin having an axial aperture and a semicircular recess, attached to said disc, a second disc located in the said lower insulating block, and contactable with said disc, a contact adjustably attached to the upper extremity of said pin, another contact normally in contact with first mentioned contact, and a coil spring superimposed between the said upper 15 insulating block and the said pin, normally holding said pin in a downward position.

4. In a device of the class described, having a heating element, the combination of a body provided with a threaded aperture, a supporting member engaged in said aperture, a lower protruding portion depending from said supporting member, a plug secured to the said protruding portion, and supporting said heating element, a lower 20 insulating block, and an upper insulating block suitably supported in said supporting member, a disc located in the lower insulating block, a pin having an axial aperture and a semicircular recess, attached to said disc, mercury housed in said axial aperture and semicircular recess, a second disc located in the said lower insulating block, and contactable with said disc, a contact adjustably attached to the upper 25 extremity of said pin, another contact normally in contact with first mentioned contact, and a coil spring superimposed between the said upper insulating block and the said pin, normally holding said pin in a downward position.

and a semicircular recess, attached to said disc, a second disc located in the said lower 40 insulating block, and contactable with said disc, a contact adjustably attached to the upper extremity of said pin, another contact normally in contact with first mentioned contact, and a coil spring superimposed be- 45 tween the said upper insulating block and the said pin, normally holding said pin in a downward position.

5. In a device of the class described, having a heating element, the combination of a body provided with a threaded aperture, a supporting member engaged in said aperture, a lower protruding portion depending from said supporting member, a plug removably attached to the said protruding 50 portion, and supporting said heating element, a lower insulating block, and an upper insulating block suitably supported in said supporting member, a disc located in the lower insulating block, a pin having an axial aperture and a semicircular recess, attached to said disc, mercury housed in said axial aperture and semicircular recess, a second disc located in the said lower insulating block, and contactable with said disc, a contact adjustably attached to the upper 55 extremity of said pin, another contact normally in contact with first mentioned contact, and a coil spring superimposed between the said upper insulating block and the said 60 pin, normally holding said pin in a downward position.

In testimony whereof I have affixed my signature.

GIUSEPPE MANASSERO.
